COUCH

Percy P. Bebry, Brookline, Mass.

Application March 22, 1935, Serial No. 12,404

8 Claims. (Cl. 5—44)

This invention relates to improvements in couches generally known as studio couches which are convertible into beds.

One of the objects of my invention is the provision of a couch of the character indicated which can be converted into a bed with minimum difficulty and which has a minimum number of operating parts.

Another object of my invention is the provision of a back rest for the cushions. In the usual construction of couches the cushions rest against the wall and inasmuch as the couch is mounted on rollers, the same has a tendency to roll away from the wall when one sits thereon and leans against the cushions. In the present invention, however, the cushions bear against a back rest which in turn is carried by a member which rests directly on the floor so that slipping of the couch is avoided.

20 A further object of my invention is the provision of a novel latching arrangement for the two sections of which the couch is composed which is readily released when it is desired to convert the couch into a bed and which will increase its latching action when pressure is applied against the back rest by one using the couch.

A still further object of my invention resides in the provision of a back rest of link spring construction and which is pivotally mounted on a stationary section of the couch so that the same may be moved about its pivot from the perpendicular position which it assumes as a back rest to a horizontal position over the stationary section for the reception of a mattress when the couch is converted into a bed.

35 A still further object of my invention is the provision of a latching mechanism of the character indicated which is carried by the back rest in such a manner that a slight forward movement 40 of the back rest about its pivot will release the latching mechanism and at the same time impart an initial forward movement to the movable section of the couch.

45 A still further object of my invention resides in the provision of a guiding or equalizing mechanism for the movable section, said mechanism maintaining the parts in proper alignment and being capable of being disconnected whereby the two sections may be entirely separated to provide 50 twin beds.

Still further objects of my invention will be manifest from the following description and the accompanying drawing in which—

Fig. 1 is a perspective view of a couch made in accordance with my invention;

Fig. 2 is a view showing the parts separated; and

Fig. 3 is a view showing the couch converted into a bed.

60 Referring to the drawing in detail, I designate

a stationary section which may take the form of a bedding compartment. This section is provided with legs 2 which rest directly on the floor, a back rest 3 made up of a wooden frame 4 having a link spring arrangement 5 secured to the frame 5 and the whole covered by fabric 6. This back rest adjacent its lower end is provided with a bracket 7 which constitutes one component of a latching mechanism and is provided with a cut-out or notch 8. The bracket 7 is bolted or otherwise rigidly secured to the back rest at 9 and is pivotally connected to the stationary compartment 1 at 10, this pivotal connection providing a pivot about which the back rest is moved, as will appear hereinafter. It will be obvious from 10 the drawing that two of such brackets are provided, one at each side of the section 1. A movable section 19 is also provided and comprises sides 20 provided with rollers 21 and an ordinary box spring 22. Each of the side members 20 is 20 provided with a pivotally mounted bracket 23 cooperating with brackets 7 and constituting the other component of the latching mechanism. Each bracket 23 comprises a flat portion 24 having a projection 25 which extends at right angles 25 to the portion 24. Each bracket is pivoted to the side member at 26, the side member being provided with a pin 27 adapted to limit the downward movement of the bracket.

It will be obvious from the description thus far 30 that when the two sections 1 and 19 are brought together or telescoped, each of the brackets 7 will engage its respective bracket 23, until the notch 8 of the bracket 7 being engaged by the projection 25 of the bracket 23 whereby the two 35 sections will be held together with the forward end of the section 1 lying beneath studs 13 or other suitable device mounted in the inside of the section 19.

The movable section 19 also carries guide rollers 40 29 to guide the two members when the same are being moved together or telescoped. There are also provided guiding or equalizing members 39 in the form of rods pivotally attached to the two sections and pivoted to each other at 34. The 45 ends of these members which are attached to the stationary section are each provided with pins 33 and 34, the pin 33 being adapted to be received by a bracket 35 on the forward side of the stationary member 1 and the pin 34 being adapted to be received by a slot 36 in a bracket 37 also mounted on the forward side of the stationary member. It will be obvious that the pins 33 and 34 may be readily lifted out of their respective brackets and the two sections 1 and 19 entirely separated so 55 that the couch may be used as twin beds. The other ends of the rods are carried in similar brackets mounted on the movable member.

I provide two mattresses 40 and 41, the mattress 40 resting upon the mattress 41 when the 60

device is used as a couch. The mattress 40 may be placed upon the back rest when the same is folded over the stationary section and the device is used as a bed.

5 It will be obvious that when the back rest 3 is pivoted about the pin 10 over upon the section 1 it will serve as a cover therefor and as a support for the mattress 40 just referred to.

10 It will be obvious from the foregoing that upon a slight forward movement of the back rest 3 about its pivot 10 the forward end of the bracket will be moved downwardly so that the notch 8 will disengage the projection 25 of the latching mechanism and also in this movement 15 the back rest will engage the mattresses and impart initial movement to the movable section to move the same away from the stationary section.

It will also be apparent that when the two 20 sections of the bed are closed, that is, as shown in Fig. 1, the studs 18 which overlie the ends or front wall of the stationary section 1 will prevent any tipping of this section upon rearward pressure being exerted upon the back rest.

25 While I have illustrated and described one embodiment of my invention, it is to be understood that I do not wish to be limited to this precise construction as it will be obvious that various modifications and changes may be made therein without departing from the spirit and scope of 30 my invention.

35 What I claim is:—

1. A convertible couch comprising a stationary section and a movable section, a back rest pivotally mounted on said stationary section and latching mechanism for latching the two sections to each other in telescopic relation, one component of said latching mechanism being mounted on the back rest and pivoted on the stationary section, the other component of the latching mechanism being mounted on the movable section.

40 2. A convertible couch comprising a stationary section and a movable section, a back rest, latching mechanism for latching the two sections to each other in telescopic relation, one component of said latching mechanism carrying said back rest and being pivoted to the stationary section of the couch, the other component of the latching mechanism being mounted on the movable section, said latching mechanism being released upon pivotal movement of the back rest toward 45 the couch sections.

50 3. A convertible couch comprising a stationary section and a movable section, a back rest, and latching mechanism for latching the two sections to each other in telescopic relation, one component of said latching mechanism being mounted on the back rest and providing a pivotal mount therefor on said stationary section the other component being mounted on the movable section, said back rest being adapted to be moved about 55 its pivot from a perpendicular position to a horizontal position over the stationary section to support a mattress when the couch is converted into a bed.

55 4. A convertible couch comprising in combination a stationary bedding compartment, a frame having a link spring secured therein, a bracket rigidly secured to said frame and pivoted to said bedding compartment to provide a pivotal mounting for said frame, said frame being movable about said pivot from an upright position to a 60 horizontal position to cover said bedding com-

partment, and a movable section comprising a box spring construction mounted on rollers and adapted to be moved relative to said bedding compartment, said bracket comprising a latching mechanism for maintaining the bedding compartment and the movable section together. 5

5. A convertible couch comprising in combination a stationary section and a movable section, a rectangular member pivotally mounted on said stationary section, said member comprising a link 10 spring construction mounted in a frame and being adapted to be moved about its pivot from an upright position to a horizontal position over said stationary section to support a mattress, the pivotal mounting for said rectangular member comprising a bracket rigidly attached thereto so as to project at an angle therefrom and be moved therewith, said bracket also providing one component of a latching mechanism, the other component of the latching mechanism being carried 15 by said movable section, the movement of said rectangular member pivoting said bracket to disengage the same from the other component of the latching mechanism. 20

6. A convertible couch comprising in combination a stationary bedding compartment, a cover for said compartment pivotally mounted thereon, a movable section, said cover comprising a link 25 spring construction mounted in a frame and adapted to be moved about its pivot from horizontal position, which it assumes when functioning as a cover for the bedding compartment and where it supports a mattress, to an upright position where it functions as a back rest, the pivotal mounting for said cover comprising a bracket 30 rigidly attached thereto so as to project at an angle therefrom and be moved therewith, said bracket also providing one component of a latching mechanism, the other component being carried by said movable section, the movement of said cover pivoting said bracket to disengage the 35 same from the other component of the latching mechanism. 40

7. A convertible couch comprising a stationary section and a movable section, a back rest pivotally mounted on said stationary section, latching mechanism for latching the two sections to each other in telescopic relation, the movable component of said latching mechanism being mounted on the back rest and providing a pivotal mount therefor on the stationary section, the other component of the latching mechanism being mounted on the movable section, the said components of 45 said latching mechanism being so disposed relatively to each other that when pressure is exerted rearwardly on the back rest when in vertical position the latching action of the latching mechanism will be increased. 50

8. In a convertible couch, the combination of a stationary section and a movable section, a link 55 spring construction pivotally mounted on the stationary section and adapted to be moved from vertical position to horizontal position over the stationary section, means for latching said sections to each other when the said link spring construction is in vertical position, said latching means being actuated by pivotal movement of said link spring construction to release the latch thereby to permit of relative movement of said sections. 60
